UNITED STATES PATENT OFFICE.

ELMO C. ROWLAND, OF MARSHALLTOWN, IOWA.

AUTOMOBILE-ENGINE ATTACHMENT.

Specification of Letters Patent. Patented Apr. 27, 1920.

1,338,534

Application filed July 21, 1919. Serial No. 312,333.

To all whom it may concern:

Be it known that I, ELMO C. ROWLAND, a citizen of the United States, residing at Marshalltown, in the county of Marshall and 5 State of Iowa, have invented new and useful Improvements in Automobile-Engine Attachments, of which the following is a specification.

The object of the invention is to provide 10 a device for use in conjunction with automobile engines, whereby the carburetor may be left undisturbed in the starting of the engine. The present engine provides for the changing of the fuel mixture in starting 15 the engine in cold or damp weather by regulating or choking the air supply to the carburetor, thus providing for a relatively rich mixture for starting without the necessity of having to open the carburetor to admit 20 additional gasoline thereto.

A further object of the invention is to provide a device of the character mentioned above which is simple in construction, durable and effective in operation and inexpensive 25 to manufacture.

Other and further objects appear in the following description wherein the invention is set forth in detail.

To the exact construction in which it is 30 described the invention is not to be restricted. The right is reserved to make such changes or alterations as the actual reduction to practice may suggest, in so far as such changes are compatible in spirit with 35 the annexed claims.

In the accompanying drawings:

Figure 1 is a view partly in section and partly in elevation showing the practical application of the invention.

Fig. 2 is a perspective view of the support 40 and part of the operating means for the choking device.

Fig. 3 is a perspective view of the plate 45 mounted on the vehicle dash and through which the end operating element of the device projects.

Fig. 4 is a view partly in elevation and partly in section of the butterfly valve used 50 to choke or cut off the air supply to the carburetor.

Referring to the drawings the invention is shown applied to a well known make of vehicle having the engine 1, the radiator 2 and the front dash 3, the usual carburetor 4 being provided and operated by the rod 5 projecting through the dash.

Since the invention contemplates the use of means for starting the engine—that is, for changing the character of the fuel mixture at starting without changing the carburetor setting, the butterfly valve 6 carried in the air supply tube 7 for the carburetor is designed for operation in the front dash. To this end the butterfly valve is provided with an arm 8 to one end of which there is 65 pivotally connected one end of a rod 9, the remaining end of the latter being pivotally connected to one end of a rocker arm 10 which is rockingly supported on a bracket plate 11 attached to the radiator 2. The remaining end of this rocker arm is pivotally connected to one end of a rod 12 which extends back in the direction of the dash and connects with one end of a bar 13, the latter passing through the dash and carrying on 75 its free end a knob 14.

A plate 15 is mounted on the front dash to which it is secured by appropriate screws and this plate 15 is provided with a slot 16 through which the bar 13 passes, the latter 80 being toothed on its under edge as indicated at 17, and the teeth engaging the bottom of the slot 16 to preclude longitudinal movement of the bar once it has been adjusted as 85 desired.

In the operation of the device, the driver of the vehicle raises the bar 13 by catching hold of the knob 14, when the teeth 17 have been disengaged from the bottom of the slot 16, the bar 13 may be moved longitudinally 90 with the result that the rod 12 is similarly moved and the rocker arm 10 shifted on its pivotal connection with the support plate 11. Such a movement of the rocker arm effects longitudinal movement of the rod 9 with 95 the consequent shifting of the butterfly valve 6. If the movement on the rod 9 is in a direction tending to close the butterfly valve 6 the air admitted to the carburetor is reduced 100 and the starting mixture thus enriched, the reverse being the case if an opposite movement is imparted to the rod 9. Obviously the rod 9 may be shifted in either direction by the proper movement on the arm 13. Therefore the butterfly valve may be moved 105 toward the open or closed position as desired and when the satisfactory running position has been obtained, the bar 13 may be allowed to drop, when the teeth 17 will engage the bottom of the slot 16 and preclude further longitudinal movement of the bar, thereby holding the butterfly valve in 110

the position in which it is desired it shall be set.

From the foregoing description and the accompanying drawings, it is believed that a clear enough understanding of the invention is to be had to render further description unnecessary.

The invention having been described, what is claimed as new and useful is:

- 10 1. The combination with an auto vehicle and carbureter therefor, of a butterfly valve mounted in the air supply pipe of the carbureter, a bracket plate mounted on the radiator of the vehicle, a rocker arm carried by the bracket plate, a connecting rod connecting the butterfly valve with the rocker arm, a bar slidably mounted in the dash, and a connecting rod connecting said bar with said arm.

2. The combination with an auto vehicle 20 and carbureter therefor, of a butterfly valve mounted in the air supply pipe of the carbureter, a bracket plate mounted on the carbureter of the vehicle, a rocker arm carried by the bracket plate, a connecting rod 25 connecting the butterfly valve with the rocker arm, a bar slidably mounted in said dash and formed with teeth on its under edge, a connecting rod connecting said bar with said arm, and a slotted plate through 30 which the said bar passes, the teeth of said bar engaging in the bottom of said slot whereby longitudinal movement of the bar may be had by raising the same to disengage the teeth so that the said valve may be operated for the purpose specified.

In testimony whereof I affix my signature.

ELMO C. ROWLAND
